UNITED STATES PATENT OFFICE.

DANIEL HAYS BUTTS, OF FREEHOLD, NEW JERSEY.

FREIGHT-CAR ATTACHMENT.

1,210,144.

Specification of Letters Patent. Patented Dec. 26, 1916.

Application filed March 15, 1916. Serial No. 84,318.

To all whom it may concern:

Be it known that I, DANIEL H. BUTTS, a citizen of the United States, and a resident of Freehold, in the county of Monmouth and State of New Jersey, have invented a new and Improved Freight-Car Attachment, of which the following is a full, clear, and exact description.

My invention relates to means for the engagement of a door-opening bar whereby to exert leverage on a door in opening or closing the same.

The doors of most box cars are very difficult to open or close, it often requiring two or three men to move the door. Very few car doors can be moved by one man unassisted but one man alone can often move the difficult doors by the use of a lever bar, though in doing so it is necessary to jab the point of the bar into the side of the car or into the door. The sides of many box cars and many car doors are marred and broken where it has been necessary to use the bar in the manner referred to. Furthermore, it is often difficult and sometimes impossible to secure a sufficient bite or purchase for the efficient use of the lever bar, by reason of which two or more men are required to open or close the door, two men often proving insufficient without the assistance of the bar and even the help of the latter is frequently small because of the difficulty in securing a bite, there being in the case of iron doors no possibility of securing a bite for the lever bar.

An object of my invention is to provide co-acting means on the door and on the car for the proper engagement of the lever bar and for its effective action on the door without damaging either the car or the door.

The invention will be particularly explained in the specific description following.

Reference is to be had to the accompanying drawings forming a part of this specification in which similar reference characters indicate corresponding parts in all the views.

Figure 1 is a front view showing my improved car and door attachments applied to a wooden car; Fig. 2 is a horizontal section on the line 2—2, Fig. 1; Fig. 3 is a transverse vertical section on the line 3—3, Fig. 1; Fig. 4 is a transverse vertical section on the line 4—4, Fig. 1; Fig. 5 is a view similar to Fig. 1, but showing another form of my in-

vention embodied in a car having a steel door, and a wood body having reinforcing metal facing members; Fig. 6 is a horizontal section on the line 6—6, Fig. 5; Fig. 7 is a transverse vertical section on the line 7—7, Fig. 5; Fig. 8 is a transverse vertical section on the line 8—8, Fig. 5; Fig. 9 is a front view showing a form of my invention embodied in a steel car and door; Fig. 10 is a horizontal section on the line 10—10, Fig. 9; Fig. 11 is a transverse vertical section on the line 11—11, Fig. 9; Fig. 12 is a transverse vertical section on the line 12—12, Fig. 9; Fig. 13 is a front view showing another form of my invention applied to a wooden car and door; Fig. 14 is a horizontal section on the line 14—14, Fig. 13; Fig. 15 is a transverse vertical section on the line 15—15, Fig. 13.

Referring more particularly to Figs. 1 to 4, my improved attachment includes a metallic strip 20 applied to the side of the car A longitudinally thereof, adjacent to the door opening 21 and at that side of the opening toward which the door moves in being opened. The said strip 20 is formed with a series of holes or depressions 21, the walls thereby constituting a longitudinal series of members each adapted to constitute a fulcrum for the point of a lever bar. The said strip 20 is applied to the car at any desired height. To coat with the strip, the door is provided with a strip 22 ranging across the same in position to be moved over the strip 20 when the door is slid. The said strip 22 projects beyond that vertical edge of the door adjacent to the strip 20 so as to overlap the latter. In the said projecting end a transverse hole 23 is formed, through which a bar may be entered to engage in one of the recesses 21. The projecting end of the strip 22 in which the opening 23 is formed is spaced from the strip 20 a sufficient distance to give clearance for the bar as the door is moved under the influence of the bar when pressed against a side wall of the said opening 23. Thus, an effective purchase of the bar may be afforded, whereby one man may start even a very tight door and move it longitudinally of the strip 20, a new bite being taken at different holes 21 when the limit of movement by one throw of the bar has been reached. The strip 22 also has a second transverse opening 24, distant from the opening 23 so that the bar may be en-

tered through either opening to engage the strip 20 according to the position of the door. In register with the opening 24 there is a larger opening 25 formed in the door to give 5 clearance in the operation of the lever bar. In addition to the strip 20 on the car, a similar strip 26 is provided below the first strip adjacent to the bottom of the door opening, said strip 26 having openings 27 similar to 10 the openings 21. The strip 26 is continued across the door opening or a separate strip 28 is applied to the car at said opening and formed with a longitudinal series of openings 29 corresponding with the openings 21, 15 27. Furthermore, the strip 28 is set in slightly from the strip 26 with which it is associated and is formed with a top flange 30 extending over the door threshold. To coat with the strips, 26, 28, on the car, a 20 strip 31 is applied to the door at the bottom edge and has transverse openings 32 therein that will register with openings 27, 29, according to the position of the door. The car as illustrated in Figs. 1 to 4 has a 25 known form of brackets *a* guiding the door at the bottom. It is to be understood that the door-hanging means do not form part of my invention.

In Figs. 5 to 8, a form of the invention is 30 illustrated in connection with a freight car having reinforcing metal strips and a steel door. In this form of the invention, separate strips 20^a are employed on a car A' at each side of a diagonally disposed metal fac- 35 ing element *a'* and each of said strips has a longitudinal series of holes 21^a. To coat with the strips 20^a and be moved over the faces of the same when the door moves, a fitting 22^a is secured thereto and projects 40 beyond the adjacent vertical edge of the door. The projecting end of the fitting 22^a is offset and provided with a transverse hole 23^a corresponding with and having the functions of the hole 23. There is also prefer- 45 ably formed in the body of the door, a hole 24^a in line with the hole 23^a and adapted also to register with the holes 21^a according to the position of the door. On the car body at the bottom, near the door opening 50 b', strips 26^a are applied at each side of the diagonal member *a'* and are formed with depressions or holes 27^a, said strips and their depressions corresponding with the strip 26 and holes 27. On the car at the bottom of 55 the door opening a longitudinal strip 28^a is applied having holes or depressions 29^a and an inturned flange 30^a, these elements corresponding with the elements 28, 29, 30. On the door B' at the bottom, to coat with 60 the strips, 26^a, 28^a, a longitudinal strip 31^a is formed on or applied to the door at the outer face and has transverse openings 32^a, the body of the door having openings 25^a at the back of the openings 32^a to afford clear- 65 ance for the lever bar after the manner of

the clearance opening 25 in the door B. The type of car illustrated in Figs. 5 to 8 has a rail *a*² and the door is formed at the lower edge to engage beneath the nose of said rail.

In applying my invention to a steel car A² as illustrated in Figs. 9 to 12, a strip 20^b is suitably riveted to the steel body of the car and is provided with holes or depressions 21^b to provide fulcrum members. The edge fitting 22^b of the door B² in this form 70 of my invention may correspond in shape with the element 22^a in Fig. 5; it is provided in its offset projecting end with a transverse hole 23^b, through which the bar may be entered. I may provide on the steel 80 door with this type of car and in line with the fitting 22^b, a steel strip 22^b having holes 24^b therein to receive the bar, said holes corresponding with the holes 24, 24^a, and permitting the entrance of a lever bar to 85 engage the strip 20^b when the position of the door disposes a hole 24^b over said strip. The steel door B² in this type of car may have clearance openings 25^b at the rear of the openings 24^b. On the car body A² ad- 90 jacent to the bottom of the door opening, a strip 26^b is suitably riveted corresponding with the strips 26, 26^a, and has depressions or holes 27^b to receive the bar. Also, at the door opening b², at the bottom, the car has 95 an additional strip 28^b in line with the strip 26^b and provided with depressions or holes 29^b and an inturned flange 30^b. The steel door B² at the bottom has a flanged angle strip 31^b suitably secured thereto, the front 100 member being offset at the front of the door and having transverse holes 32^b to receive the bar when said holes 32^b are in register with the holes 27^b or 29^b. The character *a*^b, Fig. 12, indicates a guard rail on which the 105 angle strip 31^b is supported at its ends.

In Figs. 13 to 15, I have shown my invention applied to a wooden car A³ and door B³ as in Fig. 1 but the attachment is in somewhat different form in certain of its 110 elements. The strip 20, having the openings 21, may be the same as in Fig. 1. The fitting 22^d is in the form of a cast bracket in Fig. 13 and has in the offset end a trans- 115 verse opening 23^d to align successively with the openings 21. Also, a cast fitting 22^e is shown applied to the door in line with the fitting 22^d and has an opening 24^e there- 120 through to align with the openings 21. The strip 26 having openings 27 is the same as 120 the corresponding strip in Fig. 1. The strip 28^e at the bottom of the door opening b³ is essentially the same as the strip 28, Fig. 1, and has openings 29^e together with an inturned flange 30^e shaped to correspond 125 with the formation of the car at this point. The holes 32^e in the door at the bottom, cor- 130 responding with the holes 32, 32^a and 32^b, are formed in separate cast brackets 31^e, suitably secured to the face of the door.

In the car shown the door engages a bottom guide rail indicated at a' .

It will be clear from the foregoing that an effective bite for the lever may be obtained and the door moved by one man without danger of damaging either the door or the car.

Having thus described my invention I claim as new and desire to secure by Letters

10 Patent:—

- 11 1. In a freight car, means for the engagement of a door-opening lever, said means comprising an element on the car adjacent to the doorway, said element having a longitudinal series of fulcrum members disposed lengthwise on the car, adapted to be engaged by the end of the lever, and a door having openings transversely therein, said openings being in a position for the lever to be passed through the openings and engage one of said members on the car, a wall of said openings forming a bearing surface for the lever when the latter is in engagement with one of said members.
- 12 2. In a freight car, means for the engagement of a door-opening lever, including a longitudinal series of members on the car adjacent to the door opening adapted to afford a fulcrum for the point of the door-opening lever, and a door having openings adapted to permit the passage of the lever, said openings being positioned to be alined with successive members on the car as the door is moved and thereby permit the lever to be engaged in succession with different members.
- 13 3. In a freight car, means for the engagement of a door-opening lever, said means including a longitudinal series of members on the car on a line adjacent to the bottom line of the door, and a second longitudinal series of members on the car above the first series, each of said members being adapted to constitute a fulcrum for the end of a lever, said door having openings therethrough adapted to permit the passage of the lever to engage the members of either of said series, the openings being positioned to pass in suc-

sion in front of and in line with the respective car members as the door is moved.

14 4. In a freight car, means for the engagement of a door-opening lever, said means including a longitudinal series of members on the car, each adapted to constitute a fulcrum for the point of the lever, said members being disposed in a line at one side of the door opening near the bottom and continuing across the bottom of said opening, the door having openings extending therethrough and so located as to be brought in succession in front of said members as the door is moved by the lever, a second longitudinal series of members on the car above the first series, and at one side of the door opening, each adapted to constitute a fulcrum member for the point of the lever, and an element on the car door and projecting beyond the adjacent vertical edge of the door to overlap said last-mentioned series of members on the car when the door is closed, said door element having an opening in line with the adjacent car members, walls of the openings in said element forming bearing surfaces for the lever when the latter is engaged with an adjacent fulcrum member.

15 5. In a freight car, means for the engagement of a door-opening lever, said means comprising a longitudinal series of members on the car at a side of the door opening, and an element on the car door and projecting laterally beyond the adjacent vertical edge of the door to overlap said series of members on the car when the door is closed, said door element having an opening in line with the adjacent car members and walls of the said opening forming bearing surfaces for the lever when the latter is entered through the opening and engaged with an adjacent fulcrum member on the car.

16 In testimony whereof I have signed my name to this specification in the presence of two subscribing witnesses.

DANIEL HAYS BUTTS.
